UNITED STATES PATENT OFFICE.

HERMAN R. DORE, LEWIS G. DORE, AND HARRY B. DORE, OF PORTSMOUTH, NEW HAMPSHIRE.

TRAIN-PIPE COUPLING.

1,119,814.

Specification of Letters Patent.

Patented Dec. 8, 1914.

Application filed April 17, 1914. Serial No. 832,581.

To all whom it may concern:

Be it known that we, HERMAN R. DORE, LEWIS G. DORE, and HARRY B. DORE, citizens of the United States, residing at Portsmouth, in the county of Rockingham and State of New Hampshire, have invented a new and useful Train-Pipe Coupling; and we do hereby declare the following to be a full, clear, and exact description of the invention, such as will enable others skilled in the art to which it appertains to make and use the same.

This invention belongs to the class of automatic couplers, being a combination air brake pipe, steam pipe and signal pipe coupler. Its principal object is to save time in the coupling of cars. Its operation being entirely automatic, the trainmen are not called on to go between cars and a reduction in fatalities from such causes is the result.

The design illustrated in the accompanying drawings is, at the present time considered by the inventors to be the most efficient. They reserve, nevertheless, the right to make any changes or alterations deemed necessary by the practical application of this device, if, by so doing, they do not deviate from the spirit of their subjoined claims.

In the drawings:—Figure 1 is a perspective showing the application of the combination coupler to the ordinary freight car. In this figure the main coupler is only indicated to prevent any obscurity. Fig. 2 is an end view of the device, showing principally the swing frame. Fig. 3 is a plan of the same. Fig. 4 is a longitudinal elevation, the check valve casing cover being removed and the thrust plunger being omitted. Fig. 5 is a longitudinal section of one of the universal pipe joints. Fig. 6 is a perspective of the check valve stem frame, showing its operating pawl and release rod. Fig. 7 is a view of the thrust plunger taken at right angles to that in Fig. 3.

The invention consists substantially of the valve case 1 and the coupling head 2, the brace bars 3 serving to unite them into a sanitary structure. The swing frame composed of the side pieces 4 and the top and bottom pieces 5 united by the angle irons 6 serves as a support for the coupler, the angle irons 7 securing the frame to the end sill of the car 8 immediately below the main

coupler 9. At intermediate points on the pieces 4 and 5 are studs 10 and on each of the four sides of the valve case 1 are similar studs 11 directly opposite 10. Springs 12 encompass studs 11 and 12 at their extremities, providing a resilient and universal support of the coupler as a whole.

The check valve casing 1 is molded out of solid material so as to have the chambers 13 with the incoming passages 14 and 15 and the outgoing passages 16, 17 and 18. Bosses 19 protruding into the chambers 13 are provided with holes in which the extreme end of the valve stems 20 slide. At the end remote from 19, the valve stems 20 connect with the frame 21 after passing through the passages 16 and the packing boxes 22. Valves 23 are secured by pins to these stems 20 and normally tend to close the passages 16 through the agency of the springs 24.

A cover 25 is designed to close the valve casing 1, being held thereto by means of the cap screws 26.

To the rear of the valve casing the universal pipe connections are made, such connections consisting of the longitudinal pieces 26 running the full length of the car and terminating at their ends in the globular members 27. Exterior to 27 are similar globular members 28 integral with the tubes 29 and these tubes 29 communicate with and slide in the passages 14. Globular members 27 and 28 are kept in contact by the reaction of springs 30 which surround tubes 29 and tend to push the members 28 away from casing 1.

The coupling head 2 terminates in a spherical angular nose 31 and just back of this nose is a spherical angular pocket 32 of such contour as to exactly mate with the nose, concavity fitting convexity. In coupling cars the nose of an opposing coupler mates with pocket 32 and pocket of an opposing coupler mates with nose 31.

Passages 33 and 34 are provided in the coupling head, 33 being connected to passage 18 by the tubes 35 and 34 connecting to the rubber gaskets 36 with which corresponding gaskets of an opposing coupler register.

The check valve frame 21 has integral with it a toothed member 37 with a tang 38 that projects into the pocket 32. Designed to co-act with this toothed member is a pawl 39 swung on a pin 40 which penetrates eyes

in the projections 41 integral with the coupling head 2.

A plate 42 capable of lifting the pawl 39 is attached in any suitable manner to the 5 rod 43. This rod 43 has suitable bearings in the projections 41 and terminates in handle 44.

The thrust plunger 45 has a spherical end 46 bearing against the thrust plate 47. A 10 pin 48 passes diametrically through this plunger just back of the spherical end and enters the stirrups 49 and these stirrups together with the thrust plate are connected to the valve casing 1 by suitable rivets 50. 15 A spiral spring 51 surrounds the plunger and bearing against the collar 52 connected solidly with the plunger tends to force the whole coupling forward. The plunger 45 has a suitable bearing in the car framing 20 53 in which it is capable of longitudinal movement. The method of joining the plunger to the coupler amounts to a universal connection, so that, while the plunger is only capable of longitudinal movement, the 25 coupler may be at any angle with respect to the plunger.

When cars employing the present device are coupled, the nose 31 and the pocket 32 of one coupler engage respectively the pocket 30 and nose of the opposing coupler. The passages 34 in the two couplers are designed to register and the noses 31 pressing on the tangs 38 move the valve stem frames 21 back thus opening the valves 23 and permitting 35 the passage of steam and air through their respective pipes. After the frame 21 has been moved back the pawl 39 engages the teeth of 37 and prevents the closing of valves 23 in case the train is accidentally 40 separated at any point. As modern air-brake equipment is designed to operate if the system is ruptured at any point, the advantage of this feature is readily apparent.

When it is desired to cut some cars loose 45 from the train, the rod 43 may be operated manually to close the valves 23 and preserve the system intact. The turning of the rod 43 by hand causes the plate 42 to lift the pawl 39 out of engagement with the teeth 50 of 37 when the springs 24 return valves 23 to their seats and close the system at that

point. Thrust plungers 45 keep mating couplers in continuous engagement and the universal pipe connections and the swing frame permit enough universal movement of individual couplers to meet all the requirements of practical operation. 55

The invention having been set forth, what is claimed as new and useful is:—

1. In a combination air brake pipe, steam pipe, and signal pipe system; a swing frame, a coupler swung therein, said coupler comprising a valve casing, containing spring operated valves, a coupling head, a valve opening mechanism designed to be operated by the nose of an opposing coupler, a rack and pawl for retaining it in its open position; a crank for releasing the pawl and permitting the springs to close the valves, a thrust plunger connected to the coupler and designed to keep it in continuous engagement with a mating coupler. 70

2. In a combination air brake pipe, steam pipe, and signal pipe system; a frame, a coupler suspended therein comprising a multiplicity valve casing and a coupler head, a multiplicity of passages in communication between the head and the casing, a multiplicity of spring tensioned valves controlling said passages, a valve opening mechanism carried by the coupler head to be operated by the nose of an opposing coupler head for synchronously opening the multiplicity of valves, said valve opening mechanism including a rack having a T-shaped end to engage the stems of the multiplicity of valves, a pawl engaging said rack for holding said valves open when two couplers are mating, and a member manually actuated for disengaging said pawl from the rack to permit the valves under the action of their springs to automatically close when the mating couplers are disengaged. 85 90

In testimony whereof we have signed our names to this specification in the presence of 95 two subscribing witnesses.
